US0D1040192S

(12) **United States Design Patent** (10) **Patent No.:** **US D1,040,192 S**
(45) **Date of Patent:** **** Aug. 27, 2024**

(54) **CYLINDER ICE MOLD**

(71) Applicant: **Longcheng Silicone Technology (Dongguan) Co., Ltd**, Dongguan (CN)

(72) Inventor: **Zibin Wu**, Dongguan (CN)

(73) Assignee: **Longcheng Silicone Technology (Dongguan) Co., Ltd**, Dongguan (CN)

(**) Term: **15 Years**

(21) Appl. No.: **29/937,323**

(22) Filed: **Apr. 15, 2024**

(30) **Foreign Application Priority Data**

Mar. 26, 2024 (CN) 202430160841.3

(51) **LOC (14) Cl.** **07-10**

(57) **CLAIM**

The ornamental design for a cylinder ice mold, as shown and described.

DESCRIPTION

FIG. 1 is a top perspective view of a cylinder ice mold, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

1 Claim, 8 Drawing Sheets
